UNITED STATES PATENT OFFICE.

FRANCISCO HERNANDEZ Y PEREZ, OF HABANA, CUBA.

DOUBLE LOCK.

Application filed November 11, 1924. Serial No. 749,290.

To all whom it may concern:

Be it known that I, FRANCISCO HERNANDEZ Y PEREZ, a citizen of the Republic of Cuba, and resident of Habana, Cuba, have invented certain new and useful Improvements in Double Locks, of which the following is a specification.

This invention relates to improvements in locks, the object of the invention being to provide an improved double lock which is especially adapted for use on doors but which is adapted also, for other uses and which embodies means whereby when the locking bolt is in locking position the same may be effectually locked in such position, and prevented from being moved to unlocking position by a person on the outer side of the door.

With the above and other objects in view the invention consists in the construction, combination and arrangement of devices hereinafter described and claimed.

In the accompanying drawings:

Figure 1 is an elevation of a lock constructed and arranged in accordance with this invention.

Figure 2 is a plan of the same.

Figure 3 is a vertical longitudinal sectional view of the same on the plane indicated by the line 3—3 of Figure 2.

Figure 4 is a horizontal sectional view of the same on the plane indicated by the line 4—4 of Figure 3.

Figure 5 is a similar view of the same on the plane indicated by the line 5—5 of Figure 3.

The lock case 1 is provided with a removable base plate 2, its inner side being open to receive said base plate. The case is also provided on its closed or outer side, at its front end with an extension 3 which is arranged at right angles with respect to the case and which is hollow to form a chamber 4. A slot 5 is provided in the inner side of the extension 3 and extends partly through the top of the lock case. The base plate 2 is provided with lugs 6 which bear against the inner sides of the side walls of the lock case and are secured thereto by screws 7, lugs 8 being also provided at the front end of the base plate and which bear against the corresponding wall of the lock case and are secured thereto by screws 9.

A bolt 10 which in plan is substantially T-shaped, is arranged to operate in an opening 11 in the front wall of the lock case.

A pair of rods 12 are secured to opposite sides of the bolt head as at 13 and extend rearwardly therefrom in the lock case and are provided at their inner ends with tappet bars 14 which are at right angles thereto. These rods are longitudinally movable through openings in a guide bar 15 the ends of which are arranged in recesses in inwardly extending lugs 16 with which the side walls of the lock case are provided. Coiled extensible springs 17 arranged on the said rods, bear between the bar 15 and the rear side of the head of the bolt, and act to project the bolt and normally hold the same in latching position. On its outer side the bolt is provided with a latching arm 18 which is arranged partially in the chamber 4 and is movable in the slot 5 and has a head 19 which projects out through an opening 20 in the front wall of the chamber 4. The said head has an inclined cam face 21.

A knob 22 is provided with a tubular shank 23 which is rotatably mounted in an opening 24 in the inner side of the lock case. A bearing member 25 is arranged in line with the shank 23 and is revolubly mounted at the base 2 of the lock case and is provided with an opening through which extends a key actuated operating bar 26. A cam 27 is secured to the inner end of said bar for operation thereby and a similar cam 28 is secured to the inner end of the shank 23 by a head screw 29 which is threaded in the inner end of the shank as shown, the said cams 27, 28 being arranged in spaced relation and respectively near the base and top or outer side of the lock case. Each of the said cams has oppositely extending arms 30 which bear against and are slidable on the tappets 14 of the rods 12, so that when either the knob 22 or the bar 26 is turned, one of said cams is correspondingly turned and one of the arms 30 acts upon the tappet 14 of one of the rods 12 to cause said rod to withdraw the bolt 10 against the action of the spring 17 as will be understood.

Any suitable key operated means may within the scope of this invention be employed in connection with the bar 26. For the purposes of this specification I show in Figure 1 a key operated assembly 31 such as is employed in an ordinary Yale lock and including tumblers 32.

It will be understood from the foregoing that the lock may be operated from within

the door to which it is attached by means of the knob 22 and from the outer side of the door by means of the key actuated bar 26 and its connections. A keeper 33 is provided 5 for attachment to the door jam and has a recess 34 for engagement by the head of the bolt 10, a recess 35 for engagement by the head 19 of the bolt arm 18, and also has a curved camming surface 36 for cooperation 10 with the cam face 21 of the latching head 19 to cause the bolt to be retracted and to clear the keeper when the door to which the bolt is applied is being closed. As the door to which the lock is applied reaches a nearly 15 closed position the outer end of the bolt 10 engages and slides past the camming surface 36 of the keeper so that said bolt is moved inwardly to some extent against the tension of the spring 17 and the cam surface 21 of the latching head 19 then engages the cam surface 36 and thus causes the bolt 10 to be moved completely to the extent of its 20 inward movement until the head 19 registers with the recess 35 at which instant the bolt head 10 also registers with the recess 34 so that the latching head 19 and the locking bolt head 10 are then moved, with the bolt, to projected position and in engagement respectively with the recesses 35, 34 as is 25 clearly shown in Fig. 3.

To enable the bolt to be locked so that it cannot be operated from without I provide a locking bolt 37 which is slidably mounted in the knob 22 as at 38 and is provided with a stop arm 39 which may be arranged in either of a pair of cross slots 40,

41 with which the knob is provided, the said knob also having a slot 42 which connects the cross slots and which serves to clear the arm 39 when the bolt 37 is being moved to either locking or releasing position. The said bolt 37 when in locking position engages the arm 18 of the latch bolt 10 and passes through the slot 5 as shown in Figures 1 and 3. 45

While I have herein shown and described a preferred embodiment of my invention I would have it understood that changes may be made in the form, proportion and construction of the several parts without departing from the spirit of my invention and within the scope of the appended claim. 50

Having thus described my invention, I claim:—

In a lock of the class described a casing, a latch bolt mounted for movement therein having a locking head and also a latching head, said latching head having a cam face, a spring to normally hold said bolt in projected position, and a keeper having a recess for engagement by the locking head, a recess for engagement by the latching head and also having a camming surface to cooperate with the cam face of the latching head, means including a knob to operate said latching bolt and a locking bolt mounted in said knob and arranged for longitudinal movement in either direction to hold said latching bolt in projected position or to permit release of the same. 65

In witness whereof I affix my signature.
FRANCO, HERNANDEZ y PEREZ. 70
